(57) **CLAIM**

The ornamental design for a jar, as shown and described herein.

DESCRIPTION

FIG. 1 is a top, front perspective view of the jar showing our new design;

FIG. 2 is a front elevational view thereof;

FIG. 3 is a rear elevational view thereof;

FIG. 4 is a right side elevational view thereof;

FIG. 5 is a left side elevational view, thereof;

FIG. 6 is a top plan view thereof; and,

FIG. 7 is a bottom view thereof.

The broken lines shown in FIGS. 1 and 2 are included for the purpose of illustrating a surface feature that forms no part of the claimed design.

1 Claim, 6 Drawing Sheets

FIG. 1

FIG. 2

FIG. 3

FIG. 4

FIG. 5

FIG. 6

FIG. 7
